UNITED STATES PATENT OFFICE

115,822

DESIGN FOR A PORTABLE STOVE

John R. Morgan, Oak Park, Ill., assignor to Sears,
Roebuck and Co., Chicago, Ill., a corporation of
New York

Application September 29, 1937, Serial No. 71,863

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Portable Stove, of which the following is a specification, reference being had to the accompanying drawing, forming a part thereof.

Fig. 1 is a perspective view of a portable stove in closed or inoperative position with the fuel tank and fuel regulator handles omitted, showing my new design.

Fig. 2 is a similar view of the same in open or operative condition, the handle being hidden from view.

The side of the device not seen in the drawing is similar to the side shown.

The characteristic feature of my design lies in the supporting members in association with a stove substantially as shown.

I claim:

The ornamental design for a portable stove, as shown and described.

JOHN R. MORGAN.
